E. M. JOHNSON.
SPARK PLUG.
APPLICATION FILED JAN. 27, 1919.

Patented Oct. 14, 1919.

Inventor

E. M. Johnson

By Watson E. Coburn
Attorney

UNITED STATES PATENT OFFICE.

EDWARD M. JOHNSON, OF BLYTHEVILLE, ARKANSAS.

SPARK-PLUG.

1,318,450.

Specification of Letters Patent. Patented Oct. 14, 1919.

Application filed January 27, 1919. Serial No. 273,347.

To all whom it may concern:

Be it known that I, EDWARD M. JOHNSON, a citizen of the United States, residing at Blytheville, in the county of Mississippi and State of Arkansas, have invented certain new and useful Improvements in Spark-Plugs, of which the following is a specification, reference being had to the accompanying drawings.

10 This invention relates to certain improvements in spark plugs, and it is an object of the invention to provide a novel and improved device of this general character which is constructed and assembled in a manner to eliminate substantially all possibility of breakage.

It is also an object of the invention to provide a novel and improved device of this character wherein the primary electrode is 20 subject to ventilation whereby the life thereof is materially prolonged.

An additional object of the invention is to provide a novel and improved spark plug wherein the primary electrode is disposed 25 through a body or shell and effectively insulated therefrom together with means whereby the electrode is held against displacement under the influence of an explosion.

30 The invention consists in the details of construction and in the combination and arrangement of the several parts of my improved spark plug whereby certain important advantages are attained and the device 35 rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a longitudinal sectional view taken through a spark plug constructed in accordance with an embodiment of my invention with the electrodes in elevation; and

50 Fig. 2 is a sectional view taken substantially on the line 2-2 of Fig. 1.

As disclosed in the accompanying drawings, B denotes a body or shell formed of conductive material, and preferably brass,

and which has one end portion peripherally threaded as at 1 whereby the device may 55 be properly applied in working position. The central portion 3 is angular in cross section so that the same may be engaged with a suitable tool for either applying or removing the plug.

60 The body or shell B has disposed axially therethrough a bore 4 having a portion 5 reduced at a point substantially its center and extending through the bore 4 is a primary electrode 6. Threaded upon an end 65 portion of the electrode 6 is an elongated sleeve 7 of insulating material and the combined diameter of the electrode 6 and the sleeve 7 is such as to have the sleeve 7 snugly fitting within the restricted or reduced portion 5 of the bore 4.

Also threaded upon the electrode 6 and positioned adjacent the inner end of the insulated sleeve 7 is a member or nut 8 of a diameter substantially the same as the 75 diameter of the sleeve 7 and interposed between the member or nut 8 and the inner end of the sleeve 7 is an insulating washer 9 of a diameter substantially equal to the diameter of the bore 4. The opposite end 80 portion of the electrode 6 has also threaded thereupon a second sleeve 7' of insulating material and which has its inner end abutting the member or nut 8 and its outer end terminating a slight distance inwardly of 85 the firing end of the body or shell B.

Surrounding the sleeve 7 and interposed between the washer 9 and the adjacent angular should 10 as afforded by the reduced portion 5 of the bore 4 is a sleeve 11 also of 90 insulating material. By this means it will be seen that the electrode 6 is effectively held against displacement under the influence of an explosion.

The sleeve 7' in advance of the washer 95 9 is also surrounded by a washer 12 of insulating material, and which washer has its inner end portion extending over the member or nut 8 and contacting with the washer 9 so that the sleeve 12 also serves 100 to effectively insulate the member or nut 8, which is preferably formed of metal so that the same will have the desired resistance.

The sleeve 12 terminates inwardly of the firing end of the bore 4, and inwardly of the 105 outer end of the sleeve 7' and the wall of

said bore outwardly of the sleeve 12 has in threaded engagement therewith a bushing 14 of insulating material and which bushing abuts the outer end of the sleeve 12 and 5 snugly engages the adjacent end portion of the sleeve 7. The bushing 14 also extends a slight distance beyond the adjacent or firing end of the body or shell B. The electrode 6 terminates outwardly of the bushing 10 14 as is clearly illustrated in Fig. 1. The bushing 14 serves to effectually close the working end of the bore 4 so that fouling of the electrode 6 and particularly resulting from corrosion of the body or shell B is 15 eliminated.

The opposite or outer end portion of the electrode 6 and the sleeve 7 extends exteriorly of the body or shell B and surrounding the sleeve 7 is a bushing 15 also of insulating 20 material which is threaded within the adjacent end portion of the bore 4. Threaded upon the bushing 15 is a binding member or nut 16 which contacts with the adjacent end of the body or shell B and serves to effectually lock the bushing 15 in desired position. 25

It is preferred that the outer end of the bushing 15 be substantially flush with the outer end of the sleeve 7 so that the binding washer 17 and nut 18 may be properly engaged with the extended portion of the electrode 6, so that said electrode may be properly connected with a source of electrical energy.

The electrode 6 between the inner end of 35 the bushing 15 and the reduced portion 5 of the bore 4 of the body or shell B is surrounded by an air space α in communication with the atmosphere through the ports 19 formed in the body or shell B and preferably diametrically opposed. By this it will be seen that there will be a constant flow of air through the ports 19 and the space α . This flow of air serves to effectually cool the electrode 6 whereby the life of the electrode 45 is materially prolonged.

The working or firing end of the body B at one side of the bore 4 is provided with a socket 20 in which is threaded an end portion of the secondary electrode 21 which 50 coacts with the firing or working end 6 in a well known manner.

In applying the electrode 6 the same is inserted through the body or shell B from the working or firing end thereof, and for 55 which reason the electrode 21 must of necessity be rotated in order to permit this insertion. It is also to be understood that the electrode 6 is removed from the same end of the body or shell B. In removing the 60 electrode 6, it is also to be understood that it is only necessary that the washer 17 and nut 18 be removed, and also the bushing 14.

From the foregoing description, it is thought to be obvious that a spark plug

constructed in accordance with my invention 65 is particularly well adapted for use by reason of the convenience and facility with which it may be assembled and operated, and it will also be obvious that my invention is susceptible of some change and modification 70 without departing from the principles and spirit thereof and for this reason I do not wish to be understood as limiting myself to the precise arrangement and formation of the several parts herein shown in carrying 75 out my invention in practice except as hereinafter claimed.

I claim:

1. A spark plug comprising a shell having a bore extending therethrough, an intermediate portion of the bore being restricted, an electrode extending through the bore, an insulating sleeve surrounding said electrode and snugly fitting within the restricted portion of the bore, a member threaded upon 80 the electrode and positioned adjacent the inner end of the sleeve, an insulating washer interposed between the member and the inner end of the sleeve, and a second sleeve interposed between the washer and the adjacent shoulder afforded by the reduced portion of the bore, and a second electrode engaged with the shell and coacting with the first electrode.

2. A spark plug comprising a shell having a bore extending therethrough, an intermediate portion of the bore being restricted, an electrode extending through the bore, spaced insulating sleeves surrounding said electrode, one of said sleeves snugly fitting within the restricted portion of the bore, a member threaded upon the electrode and positioned between the sleeves, an insulating washer interposed between the member and the inner end of one of the sleeves, a third sleeve interposed between the washer and the adjacent shoulder afforded by the reduced portion of the bore, a second electrode engaged with the shell and coacting with the first electrode, and a bushing of insulating material extending within the firing end portion of the bore of the body and engaging over one of the first named sleeves and terminating beyond the firing end of the shell.

3. A spark plug comprising a shell having a bore extending therethrough, an intermediate portion of the bore being restricted, an electrode extending through the bore, spaced insulating sleeves surrounding said electrode, one of said sleeves snugly fitting within the restricted portion of the bore, a member threaded upon the electrode and positioned between the sleeves, an insulating washer interposed between the member and the inner end of one of the sleeves, a third sleeve interposed between the washer and the adjacent shoulder afforded by the re-

duced portion of the bore, a second electrode engaged with the shell and coacting with the first electrode, and a bushing of insulating material extending within the firing end 5 portion of the bore of the body and engaging over one of the first named sleeves and terminating beyond the firing end of the shell, and a second bushing threaded within

the opposite end portion of the bore and surrounding the first named sleeve. 10

In testimony whereof I hereunto affix my signature in the presence of two witnesses.

EDWARD M. JOHNSON.
